RADIO RECEIVER

John C. Adams, Liverpool, N.Y., assignor to General Electric Company, a corporation of New York

Filed Dec. 28, 1964, Ser. No. 83,191

Term of patent 14 years

(Cl. D56—4)

FIG.1

FIG.2

FIG.3

FIG.4

FIG.5

FIG.6

FIG. 1 is a perspective view of a radio receiver, showing my new design;

FIG. 2 is a front elevational view, to an enlarged scale;

FIG. 3 is a fragmentary top plan view, to an enlarged scale, a portion being broken away for convenience in illustration;

FIG. 4 is a side elevational view, to an enlarged scale, the opposite side being substantially a mirror image thereof;

FIG. 5 is a rear elevational view; and

FIG. 6 is a bottom plan view thereof.

The novel features of my design reside in the provision of outwardly curved top and bottom surfaces of the radio.

Other appearance items shown, such as the placement and configuration of the clock and the radio dial and its numerals shown in broken lines, and the front panel, control knobs, and speaker grille, are for illustrative purposes only and are not considered to be essential components of my new design.

I claim:

The ornamental design for a radio receiver, substantially as shown and described.
